CLAIM

The ornamental design for a penguin bottle holder, as shown and described.

DESCRIPTION

FIG. 1 is a perspective view of a penguin bottle holder showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a top plan view similar to FIG. 6, but with the two parts of the present invention shown separately; and,
FIG. 8 is a bottom plan view thereof.

The broken lines showing of a bottle are for illustrative purposes only and form no part of the claimed design.
